UNITED STATES PATENT OFFICE

EDWARD KENNETH SANDEMAN, OF ALDWYCH, LONDON, ENGLAND, ASSIGNOR TO INTERNATIONAL STANDARD ELECTRIC CORPORATION, OF NEW YORK, N. Y., A CORPORATION OF DELAWARE

TRANSMISSION SYSTEM FOR TELEPHONY

Application filed December 12, 1930, Serial No. 501,774, and in Great Britain January 7, 1930.

This invention relates to the transmission of telephone signals over a line which gives rise to distortion resulting from interference or noise, and one object is to provide such a system wherein, having regard to these conditions, it may be so designed as to be used on a maximum energy level for a given quality of transmission.

According to one feature of the invention, 10 a system is provided wherein adjustments are made which produce for any elemental band of frequencies approximately the same number of overloads per unit of time.

According to another feature, the adjustments 15 are made so that the number of overloads per unit of time of any elemental frequency band gives an approximately constant degradation of intelligibility, i. e. independent of the location of the band in the frequency range.

According to a still further feature, a transmission line comprises a transmitting amplifier having a gain frequency characteristic designed so that having regard to the attenuation 25 frequency characteristic of the cable and the spectrum of received noise interference, the levels to which the speech energy sinks at each frequency at the receiving end of the cable, are of such magnitude that the rate of change in degradation of intelligibility 30 of speech (due to noise) due to changing the noise level by equal infinitesimal amounts in any equal elemental frequency region, tends to zero.

Other features of the invention will be disclosed in the following description having reference to the accompanying figures in which:

Fig. 1 is a curve connecting frequency in 40 cycles per second as abscissa with interfering effect in decibels as ordinates.

Fig. 2 is a curve connecting frequency (f) in cycles per second as abscissae with decibels (d) as ordinates.

In the first embodiment, a transmitting 45 amplifier is employed which has such a gain frequency characteristic that the average number of overloads per minute contributed by frequency bands of equal width is approximately independent of the location of

the band. The resultant transmitted spectrum may be referred to as an equal overload spectrum.

The receiving amplifier has such a gain frequency characteristic that the overall attenuation through the system, transmitting amplifier, cable and receiving amplifier, is independent of frequency, or conforms to any predetermined attenuation frequency curve. The gain frequency curve of the transmitting amplifier is in this case independent of the received noise spectrum.

This will be appreciated on consideration of the following:

If the nature of speech were such that only one frequency component were present at any one time, then it would evidently be desirable to transmit that one frequency at maximum power, and, if overloading were equally deleterious to intelligibility in every part of the frequency range, the optimum gain frequency characteristic for the transmitting amplifier would be one which made the probability of overloading the same in every part of the frequency range. The transmitted speech spectrum would then be quite independent of the attenuation of the cable and the noise spectrum. In default of exact knowledge of the nature of the interference spectrum an equal overload spectrum would be the spectrum which on the average might be expected to give the best performance, because the gain in transmitted level in any one part of the frequency range expressed in db in departing from an equal overload spectrum is always less than the corresponding loss which must be introduced in some other part of the frequency range also expressed in db .

When more than one frequency occurs at one time their amplitudes add directly at the peaks so that an increase in the amplitude of any one frequency can only be accomplished by reducing the amplitude of the other frequencies present, the peak being limited by the power handling capacity of the transmitting valves. If two frequencies occur at a time each of the same amplitude so that their sum is the maximum permissible peak, then by cutting down the amplitude of one to a quarter, 95

100

that is by 12 db , the amplitude of the other may be increased by 1.25 times, that is, by 5 db . The loss in transmission on the one frequency is considerably greater than the gain in transmission on the other.

5 Method of producing an equal overload spectrum

This involves a knowledge of the maximum instantaneous peak energy of speech, defined by any contour line of overload, corresponding to a given number of overloads per minute on a frequency band of given width, situated anywhere in the frequency range. This may for convenience be expressed in decibels below any arbitrary volume level by the amplification which must be applied on any band alone (all other bands being suppressed) to give a definite number of overloads per minute. This results in a separate contour line of overloading, for any chosen number of overloads per minute on one band, plotted on a plane of decibels and frequency. If the entire range is divided into n bands and the tolerable number of overloads is L per minute on normal speech for the whole range then it is proposed to choose the contour line corresponding to

$$30 \quad \frac{L}{n}$$

overloads per minute as that representing the maximum instantaneous peak energy of speech, though it is not intended to restrict the scope of this invention to this particular feature. In practice it is not expected that the shape of the contour lines will vary appreciably.

40 The maximum instantaneous peak level at any point in a circuit, in any band, may be obtained by supplying the speech from that point in the circuit to an amplifier system incorporating a band filter passing only that range, and terminating in

(a) A valve of known volume handling capacity, or,

(b) A peak voltmeter, or,

(c) Any suitable form of volume indicator.

50 In case (a) overloading may be detected either by ear or preferably by observing grid current or variation in plate current, in which case the valve becomes equivalent to a peak voltmeter. When the gain of the amplifier is adjusted so that the same conditions of overload are observed on every band, the gain of the amplifier gives for every band the ordinate of the overload spectrum of speech corresponding to the number of overloads per minute chosen, and related to the level equivalent to the setting of the peak voltmeter or volume indicator.

Thus in Fig. 2 S is the arbitrary overload

load level of the measuring valve, and the curve Q is obtained by plotting negatively from S the mean amplification which must be given to each element $a, b, c, \dots$, of the speech band to produce in that element 70 the predetermined number

$$(L)$$

of overloads per minute. It follows therefore that curve Q represents the energy spectrum of speech at the input to the amplifier.

By the insertion of an equalizer in the system under observation, immediately after the point of observation, (i. e. the input to the amplifier), having an attenuation frequency curve of the same form as the overload spectrum of speech as determined in the above manner, an equal overload spectrum may be obtained at the output of the equalizer.

In the second embodiment of the invention regard is taken of the fact that overloading at the highest frequencies in the range is tolerable since their harmonics are not reproduced and they do not mask the low frequencies when they overload.

Method of producing an equal overload intelligibility loss spectrum

The procedure for obtaining the above 95 spectrum is somewhat similar to that for obtaining an equal overload spectrum. By means of filters or equalizers part of the spectrum of a speech wave at a given point in a circuit is amplified more than the rest so that 100 any overloading which occurs in the last valve of the amplifier may be considered to be definitely due to that part of the spectrum only. After passing the overloading point the whole speech is passed through an equalizer 105 which makes the overall response of the circuit normal i. e. as would result in practice. By articulation tests a curve is plotted for each band between gain from the selected point on the circuit to the overloading point, 110 and mid band frequency. From these, articulation contour lines of gain against mid band frequency, for constant articulation, are then plotted. An equalizer is then inserted after the selected point on the circuit having an 115 attenuation frequency characteristic of the same shape as the contour line of gain against mid band frequency corresponding to zero reduction of articulation due to overloading. The speech output from the equalizer will 120 then be an equal overload intelligibility loss spectrum as defined above.

In a further modification the transmitting amplifier has such a gain characteristic that, having regard to the attenuation frequency 125 characteristic of the cable, and the spectrum of received noise interference (the overall gain or loss of the cable system, comprising transmitting amplifier, cable, and receiving amplifier conforming to any predetermined 130

dependency on frequency), the levels to which the speech energy sinks at each frequency at the receiving end of the cable, are of such magnitude that the change in degradation of intelligibility of speech (due to noise) due to 5 changing the noise level by equal infinitesimal amounts by the method described below, in any equal elemental frequency region, tends to zero. The method of reducing the noise level in any elemental frequency region is 10 here considered to comprise increasing the transmitted power in that region by the amount by which the noise level in that region is to be lower, a corresponding reduction in transmitted power being made uniformly 15 over the remainder of the range so that maximum intelligibility is obtained under the new condition. The method of determining the gain characteristic of the transmitting amplifier is by a series of articulation 20 measurements with different gain-frequency characteristics for the transmitting and receiving amplifier, the overall attenuation at each frequency being kept constant.

A preliminary gain characteristic is first 25 derived from the following:—

(a) The maximum permissible power input at the transmitting end.

(b) The peak energy spectrum of speech at the input to the amplifier taking the contour line corresponding to $\frac{L}{n}$ overloads per minute as in alternative 1.

(c) The attenuation frequency curve of 35 the cable in decibels.

(d) The noise received spectrum in voltage amplitudes on each band 100 cycles wide.

The effect of interfering frequencies depends greatly on the particular frequency 40 value, i.e., an interfering frequency of 1000 cycles would have a much more harmful effect than one of 100 cycles at the same energy level. By measuring the relative interfering effect of each frequency a transmission interference factor can be obtained from which by multiplying by the noise spectrum a curve 45 (Fig. 1) can be derived showing the relative interfering effect (as ordinates) of each 100 cycles noise band. This is then expressed 50 in decibels relative to the ordinate at 1000 cycles, taken as zero, in such a way that noise voltages greater than the 1000 cycles noise voltages are plotted positively, noise voltages smaller than the 1000 cycles noise voltage 55 are plotted negatively: this curve will be called the interference curve. The attenuation frequency curve of the cable is then plotted as positive values in decibels and the interference curve is added to it. The resultant curve gives a first approximation to 60 the slope of the gain characteristic of the transmitting amplifier. If this gives a maximum gain at or near the frequency where the speech spectrum at the input of the transmitting amplifier is also a maximum, then it

is possible that an advantage is to be gained by dropping the gain at that frequency relatively to the gain at other frequencies. Under such conditions it is proposed to observe the rule that the gain at the maximum shall 70 not exceed the minimum gain by more than (30-S) decibels, where S is the difference in level between the ordinate of the speech

energy spectrum (contour line of $\frac{L}{n}$ over- 75 loads per minute) at the frequency of maximum gain and the ordinate of the speech energy spectrum at the frequency of minimum gain, expressed in decibels. The gain slope having been determined, the optimum 80 absolute value of gain is found by experiment, by adding or subtracting distortionless gain on a resistance potentiometer.

It is evident that such instructions do not 85 specify any one curve exactly but only ensure that the first curve tried shall lie in a certain locality. Having in the above manner de-

cided on the first trial gain curve for the transmitting amplifier, an amplifier having 90 such a curve is made up, and also a corresponding receiving amplifier giving with the cable an overall attenuation of preassigned form.

An articulation test is then made on the system comprising a series of complementary changes made in the gain characteristics of transmitting and receiving amplifiers, keeping the overall attenuation at each frequency unaltered, each change being fol- 95 lowed by an articulation test. Thus an ele-

mental band of frequencies lying within the speech range is selected and the intelligibility at a particular energy level of said band is measured with the energy level of the remainder of the speech frequency range at a particular value.

Keeping the level of said band constant, the level of the remainder of the frequency range is varied above and below the condition giving maximum intelligibility to determine the condition giving maximum intelligibility. The above is then re- 100 peated with the elemental band at a succession of different energy levels above and below the condition giving a maximum value of maximum intelligibility to determine the exact condition giving maximum intelligibility.

The condition of level of the elemental frequency band and of the rest of the frequency range which gives maximum intelligibility is determined from the readings, and this gives the relationship between the level of the elemental band and the level of the rest of the frequency range for producing the maximum intelligibility.

A second elemental band of frequency is then selected and while maintaining the relation between the first elemental band and the remainder of the speech frequency range, as was determined in the first experiment, the process is repeated as before and a condition is obtained for the second

elemental band giving maximum intelligi- 110
115
120

130

bility. The above process is repeated until as many elemental portions of the speech band have been considered as are thought to be necessary. Preferably the entire frequency range would be covered. The measurement 5 may then be recommenced with respect to the first elemental band and then each one in turn as before. To reach an absolute maximum of intelligibility would require an infinite number of tests, but it has been found 10 that a useful approximation is reached by using a finite number of tests, the number depending upon the quality of transmission desired and the importance of the circuits.

It is evident that this method carried to its 15 logical conclusion will produce gain characteristics, and a resulting noise level, which are such that any complementary change in gain of finite value in either direction (and therefore change of noise level) will produce 20 a lowering of the intelligibility or conversely an increase in the degradation of intelligibility due to noise. In other words the change of degradation of intelligibility with 25 change in noise level (as carried out) is zero and the intelligibility of the circuit is the maximum possible attainable.

The invention is applicable to submarine 30 telephone cable transmission.

What is claimed is:

35 1. The method of determining the characteristic of a wave translating device for producing in a line a favourable energy level for the frequencies it is desired to transmit thereover which comprises the step of producing an equal overload intelligibility spectrum.

40 2. The method of determining the most favourable energy level of speech at a transmitting point in a line which comprises the step of determining for a small band of frequencies thereof under varying levels of the rest of the speech, the level which gives greatest intelligibility.

45 3. The method according to claim 2 wherein in the energy levels of a plurality of elementary bands of frequencies within the speech range are each moved relatively to the level of the rest of the range, to determine for each 50 band the level relationship giving greatest intelligibility, establishing this level relationship and thereafter if necessary adjusting the level of the entire range to produce under the established conditions the maximum of intelligibility.

55 4. The method of improving a transmission system subject to noise interference which comprises so designing the gain characteristic of the transmitting amplifier thereof 60 with regard to the attenuation frequency characteristic of the cable and the spectrum of received noise interference that when the noise level is changed by equal infinitesimal amounts in any equal elemental frequency 65 region the speech energy level for each fre-

quency at the receiving end of the cable sinks to such a degree that the rate of change in degradation of intelligibility of speech due to noise tends to zero.

In witness whereof, I hereunto subscribe 70 my name this 18th day of November, 1930.

EDWARD KENNETH SANDEMAN.
